DESIGN FOR A SHOE

James C. Pape, New York, N. Y.

Application May 12, 1934, Serial No. 51,761

Term of patent 3½ years

To all whom it may concern:

Be it known that I, JAMES C. PAPE, a citizen of the United States and resident of the city of New York, in the county of New York and State of New York, have invented a new, original, and ornamental Design for a Shoe, of which the following is a specification, reference being had to the accompanying drawing forming part thereof, in which,

Fig. 1 is a side elevation of a shoe showing my new design; and

Fig. 2 is an elevational view of the opposite side of the shoe shown in Fig. 1.

I claim:

The ornamental design for a shoe, as shown.

Dated May 3, 1934.

JAMES C. PAPE.
